FIG. 1

FIG. 2

FIG. 3

FIG. 4

FIG. 5

FIG. 6

FIG. 7

FIGURE 1 is a front perspective view of a photographic camera or similar article showing our new design;
 FIG. 2 is a rear view thereof;
 FIG. 3 is a front view thereof;
 FIG. 4 is a side view thereof;
 FIG. 5 is a view of the other side thereof;
 FIG. 6 is a bottom view thereof; and
 FIG. 7 is a top view thereof.

The essential features of our design reside in the parts shown in full lines. A carrying strap is fragmentarily represented by broken lines in FIGS. 1, 3, 5, 6 and 7 for illustrative purposes only.

We claim:
 The ornamental design for a photographic camera or similar article, substantially as shown and described.
